UNITED STATES PATENT OFFICE.

JOHN W. McLEOD, OF NEW YORK, N. Y.

GAME APPARATUS.

1,365,712.

Specification of Letters Patent. Patented Jan. 18, 1921.

Application filed October 11, 1919. Serial No. 329,936.

To all whom it may concern:

Be it known that I, JOHN W. McLEOD, a citizen of the United States, and residing at New York, in the county of New York and State of New York, have invented certain new and useful Improvements in Game Apparatus, of which the following is a specification, such as will enable those skilled in the art to which it appertains to make 10 and use the same.

This invention relates to game apparatus and particularly to what is known as billiard and pool tables and more particularly to tables of the class specified designed to 15 be used in connection with boats, vessels, ships and the like which are constantly in motion either rolling or pitching while at sea; and the object of the invention is to provide an improved mounting or support 20 for tables of the class specified which is designed to keep the table in a horizontal position at all times regardless of the position of the ship or other support in connection with which it is mounted; a further object 25 being to provide an improved floor or platform construction which co-operates with the table and which is mounted in such manner as to retain a horizontal position regardless of the position of the ship or other support 30 upon which or in connection with which it is mounted; and with these and other objects in view the invention consists in an apparatus of the class and for the purpose specified, constructed and operating as 35 hereinafter described and claimed.

The invention is fully disclosed in the following specification, of which the accompanying drawing forms a part, in which the separate parts of my improvement are 40 designated by suitable reference characters in each of the views, and in which:—

Figure 1 is a plan view of a floor or deck of a ship showing my improved billiard table and supplemental floor or platform 45 mounted in connection therewith;

Fig. 2 a partial section on the line 2—2 of Fig. 1;

Fig. 3 a partial section on the line 3—3 of Fig. 2; and,

Fig. 4 a partial section on the line 4—4 of Fig. 2.

In the drawing I have indicated at 5 a part of a deck or floor of a ship which is cut out to form a large rectangular and elongated aperture 6 below which the ship is provided with a compartment or chamber

7. At 8 I have shown a supplemental floor or platform, at 9 a billiard or pool table and at 10 a standard or support for the supplemental floor or platform 8 and table 9. 60

The support 10 comprises a base 11 securely mounted in connection with the bottom of the chamber 7 and provided with an upwardly directed portion 12, the top of which is forked as shown at 13 in Fig. 4 65 of the drawing. Passed transversely through the forked end of the support 10 is a pin or shaft 14.

Mounted on the shaft 14 between the separate parts of the forked end of the support 70 10 is a frame 15 provided with a central bearing 16 which permits of the free rotation of said frame on the shaft 14. The frame 15 is provided with oppositely directed arms 17 having reduced trunnions 18 75 which pass through bearings 19 mounted in brackets 20 secured to the bottom face of the table 9. The mounting of the arms 17 in the brackets 20, as above set out, permits of the transverse rotary movement of the 80 table 9 on the frame 15, or a rotary movement of said frame in a transverse plane in the brackets of said table, and this movement combined with the rotary movement of the frame 15 on the support 10 forms a 85 universal connection of the table 9 with the support 10 as will be apparent.

The table 9 is provided with a sheet metal inclosing hood 21, which is secured to the bottom face of the table and is designed to 90 inclose the frame 15 and the various parts connected therewith within said hood, and said hood also passes downwardly through and operates in a central circular aperture 22 in the supplemental floor or platform 8, 95 as clearly shown in Figs. 1, 3 and 4. The hood 21 is also preferably provided with four downwardly directed extensions 23 arranged at right angles to each other and preferably at an angle of forty-five degrees 100 to the longitudinal and transverse plane of the table 9, and weights 24 are mounted in connection with said extensions and serve to balance the table 9 or hold the same at all times in a horizontal position. It will, therefore, be seen that if the ship 5 as well as the support 10 mounted in connection therewith should pitch, either forwardly or backwardly or roll laterally, this movement would not be transferred to the table 9, and 110 said table would always assume a horizontal position thus preventing any movement of

the billiard or pool balls on the table or any other game devices that may be used in connection therewith.

I also preferably support the supplemental floor or platform 8 in the same manner as the support of the table 9 and in accomplishing this result I employ a supplemental frame member 25 which is provided with a central yoke-shaped portion 26 provided 10 with an upwardly directed forked portion 27 through which the shaft 14 passes as clearly shown in Fig. 4. The supplemental frame member 25 is provided with oppositely directed arms 28, the free ends of 15 which are provided with trunnions 29 which pass through bearings mounted in brackets 30, secured to the bottom of the supplemental floor 8 as clearly shown in Figs. 2 and 3. From the foregoing it will be seen that the 20 supplemental frame member 25 is free to oscillate on axes arranged at right angles to each other, whereby the pitching of the ship 5, or the rolling movement thereof, will not be imparted to the supplemental floor 8.

25 A sheet metal guard 31 is secured to the bottom of the floor 5 of the ship and extends downwardly into the chamber 7 to a slight extent to prevent parties from being caught between the floor 5 and the supplemental 30 floor 8 in the pitching or rolling movements of the ship. The supplemental floor 8 is held in a horizontal position by balance-weights 32 mounted in semi-circular holders 33 secured to the bottom face of the supplemental floor 8, preferably in the manner indicated in Figs. 2, 3 and 4 of the drawing.

It will be apparent that the weights 32 will be sufficient to support a predetermined 40 number of players or parties on the supplemental floor 8 without moving said supplemental floor out of a horizontal position to any great extent. I also preferably employ two spiral springs 34—34, which are connected with the bottom face of the supplemental floor 8 adjacent to, and centrally of, the short sides thereof, and these springs are also connected with the bottom of the chamber 7, and the object of these springs is to prevent or limit the pitching movement 45 of the supplemental floor 8 should a party or parties accidentally jump or fall upon the supplemental floor at the side portions thereof, where the springs 34 are connected therewith, which would cause a sudden 50 downward movement of the supplemental floor.

For the purpose of making the description above set out clear, it must be understood that the table 9 and supplemental 60 floor 8 are arranged longitudinally of the ship, or the long sides of said table and supplemental floor are in a plane parallel with a longitudinal plane of the ship, while the other sides are in a plane parallel to a 65 transverse plane of the ship. Thus when

the ship pitches either forwardly or backwardly, the frame 15 and supplemental frame member 25 will correspondingly rotate or oscillate on the shaft 24, while in the rolling or lateral movement of the ship 70 said frames will rotate in the brackets 21 and 31.

With my improved mounting for billiard tables, pool tables and the like as well as the mounting for the supplemental floor or 75 platform 8, the desired game may be played without interference, or without experiencing any difficulty, whatever, regardless of the movement of the ship, it being understood that the weights 24 will be sufficient to 80 withstand the weight of the body of a player resting thereon at any particular point without materially affecting the position of the table. It will be understood that my invention is not necessarily limited to 85 the mounting of billiard tables in the manner set out, nor is the invention limited to the particular apparatus in connection with which the game table is mounted, and various changes in and modifications of the de- 90 tails of construction herein shown and described may be made, within the scope of the appended claims, without departing from the spirit of my invention or sacrificing its advantages.

It will also be apparent that in the accompanying drawings I have exaggerated the size of the supports of the table and platform, but this is done merely to clearly illustrate the various bearings employed 100 and, in practice, all of the parts of the apparatus will be made in proportionate sizes and of the required length.

Having fully described my invention, what I claim as new and desire to secure 105 by Letters Patent, is:—

1. An apparatus of the class described comprising a table, a support, means for universally connecting said table with said support, means for holding said table normally in a horizontal plane, a platform co-operating with said table, means for universally supporting said platform, and means for normally holding said platform in a horizontal plane. 110

2. An apparatus of the class described comprising a table, a support, means for universally connecting said table with said support, balance-weights for normally holding said table in a horizontal plane, a platform co-operating with said table, means for universally supporting said platform, and balance-weights for normally holding said platform in a horizontal plane. 115

3. An apparatus of the class described comprising a table, a support, means for universally connecting said table with said support, balance-weights for normally holding said table in a horizontal plane, a platform co-operating with said table, means 120

for universally supporting said platform, balance-weights for normally holding said platform in a horizontal plane, and tensional means connected with said platform 5 and with a stationary support.

4. In a game apparatus for use in connection with ships, a table, a support mounted in connection with the ship, a frame rotatably mounted in connection with 10 said support and said table whereby said table is universally mounted on said support, a platform coöperating with said table, a supplemental frame rotatably connected with said support and said platform where- 15 by said platform is universally mounted in connection with said support and balance-weights for normally holding said platform in a horizontal plane.

5. In a game apparatus for use in connection with ships, a table, a support mounted in connection with the ship, a frame ro- 20

tatably mounted in connection with said support and said table whereby said table is universally mounted on said support, a platform coöperating with said table, 25 a supplemental frame rotatably connected with said support and said platform whereby said platform is universally mounted in connection with said support, balance-weights for normally holding said 30 platform in a horizontal plane, and spiral springs connected with said ship and with said platform.

In testimony that I claim the foregoing as my invention I have signed by name in 35 presence of the subscribing witnesses this 9th day of October 1919.

JOHN W. McLEOD.
